MUSHROOM-BULLET.

1,095,502.

Specification of Letters Patent. Patented May 5, 1914.

Application filed February 24, 1914. Serial No. 820,625.

To all whom it may concern:

Be it known that I, FRANK O. HOAGLAND, a citizen of the United States, residing at Bridgeport, county of Fairfield, State of Connecticut, have invented an Improvement in Mushroom-Bullets, (Case E,) of which the following is a specification.

This invention relates to full covered or jacketed bullets of the class in which the body cover and the tip cover are made separate, and has for its object to provide a bullet of this type which while retaining the ordinary properties of covered bullets will mushroom, *i. e.* flatten out upon impact with an objective. This result I accomplish by providing the tip cover with alternate ribs and grooves and then swaging the ribs down upon the tapering portion of the bullet so that the surplus metal of the ribs will lie in the form of folds.

In the accompanying drawing forming a part of this specification, Figure 1 is an elevation of my novel bullet; Fig. 2 a rear elevation of the tip cover as formed; Fig. 3 a rear elevation of one form of completed tip cover detached; Fig. 4 a rear elevation of a completed tip cover varying from Fig. 3 in that the folded metal is disposed differently, and Fig. 5 is a view showing the bullet mushroomed by impact with an objective.

10 denotes the core of my novel bullet, which is made of relatively soft metal, 11 the body cover and 12 the tip cover. The gist of the invention lies in forming the tip cover from a disk of metal and corrugating it in the process of formation as shown in Fig. 2. The cover is formed of greater width at its base than the diameter of the bullet and is provided with alternate ribs 13 and grooves 14, giving to the tip cover as formed somewhat the appearance of a partly opened umbrella. The ribs and grooves are of course widest at the rear end of the cover and run out well toward the apex thereof. 45 This partly formed umbrella shaped cover is then placed on the tapering portion of the bullet and swaged down to place, as shown in Figs. 1 and 3, the metal of the completed tip cover lying in folds 15 which in this 50 form extend in opposite directions from the centers of the ribs from which the folds are formed.

The form illustrated in Fig. 4 differs only in that in the swaging process the swaging die has imparted to it a slight rotary movement, the effect of which is to close down the ribs in the form of folds 16 which extend in one direction only, like the folds of an umbrella when rolled.

I preferably provide some simple means 60 for insuring the retention of the tip cover upon the tapering portion of the bullet. Just how this is effected, however, is wholly immaterial so far as the principle of the invention is concerned. In the present instance I have shown the tip cover as retained in place by striking in holding points 17 from the metal of the tip cover and forcing them into the core as indicated in Fig. 1.

In use, when my novel bullet strikes an objective it mushrooms somewhat as indicated in Fig. 5, the folds of the tip cover opening out like the folds of an umbrella. This for the reason that the momentum of the mass of the bullet easily overcomes the resistance 75 of the folded tip cover which will open out as already explained and the entire forward end of the core will mushroom under the cover.

Having thus described my invention I 80 claim:

1. A bullet of the character described having its tip cover provided with alternate ribs and grooves, the ribs being swaged down upon the tapering portion of the bullet in 85 the form of folds which open out like an umbrella upon impact with an objective.

2. A bullet of the character described having a tip cover formed with alternate ribs and grooves which are closed down upon the 90 tapering portion of the bullet.

3. A bullet of the character described having its tip cover formed with alternate ribs and grooves, the ribs being closed down upon the tapering portion of the bullet in the 95 form of folds extending in opposite directions from the center of the ribs.

In testimony whereof I affix my signature in presence of two witnesses.

FRANK O. HOAGLAND.
